UNITED STATES PATENT OFFICE

GERALD THOMAS, OF NEW YORK, N. Y., ASSIGNOR OF ONE-FOURTH TO GODFREY NURSE, OF NEW YORK, N. Y.

WINDOW-SASH CONSTRUCTION

Application filed August 11, 1928. Serial No. 299,041.

This invention relates to improvements in window sashes and more particularly to a window sash of the sliding type.

The prime aim of this invention is to obviate the necessity which at present compels window washers to expose themselves exteriorly of a window in order to properly clean the same, thus subjecting themselves to considerable danger and frequently because of the imminence of this danger the outer side of the sash is not thoroughly cleaned.

The prime object of this invention therefore is to provide a side construction for windows wherein the pane may be reversed within the sash frame to permit the cleaning of both sides thereof without endangering the person so working.

Another important object of the invention is to provide a window sash construction of the above nature capable of being easily adjusted to reversed position and being of such simple construction as to allow the manufacture thereof at a cost only slightly above the cost of the present type of sash.

Still another object resides in the means employed for connecting the reversible pane to the sash frame whereby the pane may be swung completely inward of the sash frame and reversed to a position convenient to the person cleaning the same.

After reading the following specification and claims, other important objects and advantages of the invention will become apparent.

In the drawing:

Figure 1 is an inside elevation of a window construction equipped with the present improved sash structure,

Figure 2 is an edge elevation of the window frame partly broken away and disclosing the inner frame of the lower sash disposed partly away from the sash frame, while the dotted lines disclose the position the inner frame will assume when in complete reversed position,

Figure 3 is a side elevation of the improved sash construction,

Figure 4 is a horizontal sectional view through the window frame and one of the

improved sashes taken substantially on line 4-4 of Figure 1, and looking in a downward direction, and

Figure 5 is a vertical sectional view through a fragmentary portion of the invention disclosing the means employed for securing the inner frame to the outer frame of each sash construction.

Referring to the drawings wherein like numerals designate like parts, a window frame A is provided in the usual manner with the guide strips B between which the sashes are slidable.

The present invention relates to improvements in slideable sashes and are engageable with the window frame in the usual manner. As the upper and lower sashes of a window construction such as is disclosed in Figure 1 of the drawings are identical, the description of one will suffice for both.

The sash consists of an outer frame 1 provided with an inwardly disposed flange 2 arranged continuously within the frame. The inner vertical edge portions of the outer frame 1 are formed with elongated channels 3-3.

The portion of the flange 2 at the top of the outer frame 1 has a plate 4 secured to its outer side and is formed with a threaded opening therein in registry with an opening through the flange 2.

The sash also includes an inner frame 5 within which a transparent pane 6 is mounted. Obviously, this pane need not necessarily be of a single sheet, as the inner frame 5 may be allotted into numerous divisions devised to retain a plurality of panes if desired.

An elongated arm 7 is pivotally secured at one of its ends to the upper end portion of each channel 3-3 of the outer frame 1. Each vertical edge of the inner frame 5 is formed throughout a major portion of its length with an undercut groove. A plate 8 is formed throughout its intermediate longitudinal portion with an undercut channel, and this intermediate portion is disposed within the undercut groove of the inner frame edge in the manner designated by numeral 9.

The opposite ends of the arms 7 are equipped with laterally disposed protuber-

ances 10 each having an enlarged head 11 engaged within the undercut channel of the plate 8.

Obviously, by moving this latter end portion of each of the arms 7 to the lowermost portion of the plate 8, the inner frame may be disposed within the outer frame in the manner shown in Figure 1.

10 A threaded bolt 12 provided with a wing head 13 is engageable through an opening in the upper portion of the inner frame 5 while its threaded end portion may be fed into the threaded opening of the plate 4 whereby to secure the inner frame within the outer frame.

15 16 By unscrewing the bolt 12, the inner frame 5 may be pulled outwardly of the outer frame to a position as shown in Figure 2. By effecting a substantial horizontal pull on the upper end of the inner frame, the outer ends 29 of the arms 7 will be disposed toward the opposite end of the slotted plate 8.

In this manner the inner frame will assume a reversed position whereby the pane may certainly be easily cleaned.

25 26 Obviously, certain changes in the specific shape, size or materials may be resorted to without departing from the spirit or scope of the appended claims.

Having described the invention, what I

30 claim as new is:

1. In a sash structure comprising an outer slide frame, an inner frame engageable with in the outer frame, said inner frame being formed with a pair of its opposite edges 35 grooved, and a pair of arms pivoted at one of their ends to the outer frame and having their opposite ends slidably engaged within the grooved edges of the arms whereby the same inner frame may be moved outwardly 40 of the outer frame and swung to a reversed position.

2. In a sash structure comprising an outer frame, an inner frame for supporting a transparent pane, and means for reversing said inner frame within the outer frame, said means consisting of a link pivotally connected to the outer frame and slidably connected to the inner frame.

45 In testimony whereof I affix my signature.
GERALD THOMAS.
